UNITED STATES PATENT OFFICE.

WILLIAM S. TURNER, OF GREENSBURG, PENNSYLVANIA.

HOT-AIR FURNACE.

No. 849,177.

Specification of Letters Patent.

Patented April 2, 1907.

Application filed December 21, 1906. Serial No. 348,928.

To all whom it may concern:

Be it known that I, WILLIAM S. TURNER, a citizen of the United States of America, residing at Greensburg, in the county of Westmoreland and State of Pennsylvania, have invented certain new and useful Improvements in Hot-Air Furnaces, of which the following is a specification, reference being had therein to the accompanying drawings.

10 This invention relates to hot-air furnaces especially adapted for use in dwellings; and its object is to provide a simple and inexpensive gas-heater for use in combination with a register to heat a building.

15 The construction of the improvement will be fully described hereinafter in connection with the accompanying drawings, which form part of this specification, and its novel features will be defined in the appended claims.

20 In the drawings, Figure 1 is a front elevation of a furnace embodying the invention. Fig. 2 is a vertical section of the same. Fig. 3 is a vertical section taken at right angles to the section-line of Fig. 2; and Fig. 4 is a view 25 in perspective, partly broken away, of one of the air-deflecting plates employed.

The furnace is designed to be suspended below the lower floor of a building in communication with a register.

30 The reference-numeral 1 designates a shell or casing preferably square in cross-section and open at top and bottom.

35 A gas-burner 2 is arranged within the lower portion of the casing, fed from a suitable supply-pipe 3, and the casing is provided at one side with an opening 4, through which the burner is lighted, said opening having a closure 5.

40 Projecting from opposite sides of the upper edge of the casing are a suitable number of L-shaped lugs 6 to support a conical head 7, provided with a square depending flange 8, adapted to rest on said lugs. The upper end of the hood 7 fits within the depending rim 9 of a register 10, fitting an opening in the floor 11.

The furnace is suspended below the floor by wires 12 or other suitable suspending means, secured at their upper ends to the floor-support 13 and at their lower ends to the lugs 6, as shown.

To opposite sides of the casing 1 are secured deflector-plates 14, each provided with

laterally-projecting flanges 15 and formed at its upper end with a hook 16, adapted to engage the upper edge of the casing.

55 The plates 14 are secured to the casing by rivets 17, extending through the flanges 15 and hooks 16, and the lower ends of said plates extend out from the sides of the casing 60 to provide air-chambers 18, communicating with the interior of the casing through openings 19, formed in the opposite walls of the casing.

65 Within the casing 1, above the burner, is secured a hollow V-shaped deflector 20, which serves as a spreader for the flame from the burner.

70 The utility and operation of the furnace constructed as thus described will be readily understood. Air entering through the lower open end of the casing is heated in its passage to the conical drum 7, and the air which enters through the lower open ends of the air-chambers 18 passes into the casing 1 75 through the openings 19, admixing with the air within the casing above the V-shaped spreader 20.

80 What I claim, and desire to secure by Letters Patent, is—

1. A hot-air furnace comprising a casing open at the top and bottom and having openings in its side walls, a conical hood supported thereon, a gas-burner within the lower portion of the casing, a V-shaped spreader 85 above said burner, and deflector-plates on opposite sides of said casing forming air-chambers which communicate with the openings formed in the side walls of the casing. 90

2. A hot-air furnace comprising a casing open at top and bottom and having openings in its side walls, a conical hood supported thereon, a gas-burner within the lower portion of the casing, a V-shaped spreader 95 above said burner, and deflector-plates secured to opposite sides of the casing to provide air-chambers, communicating with the openings formed in the side walls of the casing, and having laterally-extending flanges 100 and hooks to secure them to the casing.

3. The combination with a register, of a hot-air furnace suspended below the register and comprising a casing provided at its upper end with projecting lugs and having 105 openings in its side walls, a conical hood

resting on said lugs, a gas-burner within the lower portion of the casing, a V-shaped spreader above the burner, deflector-plates secured to opposite sides of the casing to provide air-chambers communicating with the casing through the openings in the side walls thereof.

In testimony whereof I affix my signature in the presence of two witnesses.

WILLIAM S. TURNER.
